UNITED STATES PATENT OFFICE.

WILLIAM H. JACKSON AND JOHN H. HANKINSON, OF NEW YORK, N. Y.

DESIGN FOR A FIRE-PLACE BACK.

SPECIFICATION forming part of Design No. 14,462, dated December 4, 1883.

Application filed October 12, 1883. Term of patent 7 years.

To all whom it may concern:

Be it known that we, WILLIAM H. JACKSON and JOHN H. HANKINSON, citizens of the United States, residing at the city of New York, in the county and State of New York, have invented and produced a new and original Design for Fire-Place Backs or Jambs, of which the following is a specification, reference being had to the accompanying drawing, forming part thereof.

The drawing represents this new design in elevation.

This design in its general characteristics is similar to that for which we filed an application for Letters Patent July 25, 1883; and the specification in that application may be referred to in connection with the following description, in which the distinguishing feature of this design is set forth.

20 The distinguishing prominent feature of this design consists of an artificial stand or trunk of a shrub or small tree, which has laterally-outspreading limbs and foliage resembling the myrtle, above a balustrade, as shown in the drawing. This figure, with gracefully-curved limbs, is represented as having an artificial stand or trunk consisting of an intertwining wreath at the bottom, folds of drapery at the center, and three groups of flowers and leaves, 25 as in vases, arranged in vertical line at the

top. The two lower branches of the shrub, with large swelling scraggy bodies, terminate with dolphin-like heads above the balustrade that extends across and forms the lower section of the design. Each of these two lower 35 limbs divides into two reverse-curved terminal branches and extend upward, ending in scroll-like curves, with flowers as a center.

The balustrade consists of open-work with coping or rails along its top. The lower 40 branches, with curved scaly bodies, have ideal dolphin-like heads that are in close proximity to the lower portion of the artificial trunk and appear as connected therewith and resting upon the railing of the balustrade.

Having described our design, we claim—
15 The design for fire-place backs or jambs herein shown and described, consisting of the representation in relief of a shrub or tree with foliage like the myrtle, with an artificial 50 trunk composed of the figures of a wreath, drapery, and vases of flowers, and with ideal dolphin-like branches above a balustrade.

Witness our hands this 28th day of August, A. D. 1883.

WILLIAM H. JACKSON.
JNO. H. HANKINSON.
